POSITION INDICATOR MECHANISM FOR ELEVATORS

Arthur Ennis Prince, Boonton Township, Morris County, N.J., assignor to Otis Elevator Company, New York, N.Y., a corporation of New Jersey

Filed Oct. 20, 1958, Ser. No. 768,368

7 Claims. (Cl. 340—21)

This invention relates to position indicating mechanism for elevators.

In elevator installations it is usual to provide a device that indicates the positions of the various cars in their respective hoistways. Also, it is usual to indicate this information visually on one or more strategically placed panels by means of sequentially energized electric light sources positioned in a row for each car, each light source in the row corresponding to a floor landing served by the car. Such a panel is usually located at the main lobby served by the elevators, where it is accessible to the "starter" and to intending passengers so that they may know from the position of each car in relation to the other cars which car will probably be next to arrive at the lobby. A similar panel is occasionally located in the maintenance center of the building, to portray visually the operation of the elevators for the benefit of maintenance personnel. The position of a particular car is also usually portrayed visually to passengers traveling in that car by means of similar sequentially energized electric light sources located within the car so that they may know the position of the car and when the car arrives at their destination.

In such prior art devices during a large portion of the period the car is between floors in its travel, there is no indication of its position as neither the light source for the floor landing it has left nor the one for the floor landing it is approaching is energized. These "gaps" in the indication of the position of the car are undesirable, inasmuch as the starter and intending passengers cannot readily ascertain the relative positions of the cars by merely glancing at the panel for an instant, but must prolong their observations. Passengers within a car are likewise handicapped by these "gaps" in car position indication and must prolong their observations before they can get ready to leave a car as it approaches their destination. Furthermore, in case a car becomes stranded between floor landings, the maintenance personnel cannot quickly determine where in the hoistway the stranded car is located.

It is therefore an object of this invention to provide car position indicator mechanism which continuously gives an indication of the position of each car in its hoistway.

In the preferred embodiment of the invention, the foregoing objective is accomplished without providing additional indicating equipment by maintaining a previously energized light source illuminated substantially until the next light source is energized. Toggle switches are mounted on floor bars of the car's selector for interconnecting an energy source to the light source provided for each floor landing. A cam mounted on the crosshead of the selector actuates these switches sequentially, as the crosshead moves, simulating the movement of the car. These switches are of a fast acting type and are interconnected with the light sources in such a manner that as a previously energized light source is deenergized,

2

the next light source is instantaneously energized. This instantaneous transfer from one light source to another coupled with the normal persistence of human vision is effective to give a continuous indication of the position of the car as it travels in its hoistway.

Features and advantages of the invention will be apparent from the above and from the following description of operation when considered in conjunction with the drawings in which:

10 Figure 1 is a simplified schematic representation of an elevator installation including control mechanism actuated in accordance with car movement and embodying the invention;

15 Figure 2 is a side elevational view in fragmental detail of one form of the toggle switches embodied in the control mechanism of Figure 1;

20 Figure 3 is a cross-sectional view of the same toggle switch taken approximately along the line 3—3 of Figure 2;

25 Figure 4 is a front elevational view of the toggle switch shown in Figure 2 with the switch in position for cooperating with a cam actuated in accordance with car movement; and

30 Figure 5 is a simplified schematic wiring diagram of the position indicating circuits embodying the invention.

Referring to Figure 1, the hoisting rope 10 passes over the hoisting sheave 11 and connects the car 12 to the counterweight 13. The motor 14 drives the sheave 11, thus effecting the raising and lowering of the car and counterweight. Control mechanism driven in accordance with car movement is illustrated schematically as a simplified form of selector machine driven preferably by means of a steel tape 15 attached to the car 12 and counterweight 13 and having teeth formed thereon for engaging teeth on the selector driving wheel 16.

35 The selector machine comprises a frame formed by a base plate 17 and a top plate 18 supported from the base plate by standards 20, one of which for convenience is illustrated as a guide bar 19. The driving wheel 16 is secured to the outer end of a shaft 21 rotatably supported on base plate 17. A vertical screw 22 is driven by shaft 21 through the intermediary of bevel gears 23. The vertical screw 22 drives crosshead 24, which is guided in its vertical movement by guide bar 19.

40 Floor bars 26 are attached to standards 20 at predetermined points corresponding to the relative location in the building of the floor landings served by the car. Each floor bar 26 except the floor bar corresponding to the lowermost floor landing has a toggle switch TS1 to TS4, mounted thereon in vertical alignment with each other in position to be engaged and actuated by cam C carried by crosshead 24, as the crosshead moves along its vertical path.

45 Details of toggle switches TS1 to TS4 are shown in Figures 2 and 3. The various parts are shown mounted on a switch housing consisting of two insulating members 34 and 35 which in turn are mounted on a selector floor bar 26 by means of three studs 37. These studs pass through apertures in floor bar 26 (but do not touch it) and housing members 34 and 35 and are secured in place by nuts 38 and lock washers 39. The threaded end portion of studs 37 are made long enough to serve as terminals for connecting the various electrical leads illustrated in the position indicator lamp circuit of Figure 5.

50 The heads 41 of two of the studs 37 have formed thereon stationary contacts 43 and 44, respectively, of silver material. Defined in the head 46 of the third stud 37 is a groove 47 which forms a pivot for metallic switch lever 51, having a substantially cross shape with one end of its vertically extending member 51a pivotally positioned in groove 47. Its horizontally extending mem-

ber has affixed at one end a contact 54 which engages with stationary contact 43 when switch lever 51 is in one extreme position, and at its other end a contact 55 which engages with stationary contact 44 when switch lever 51 is in the other extreme position. A substantially U-shaped toggle link 57 having a web portion 57a is pivotally secured to housing member 35 by means of two pins 58. Shoulders 59 and 60 formed in housing member 35 act as stops to limit the movement of toggle link 57. A roller 62 of insulating material is rotatably secured to toggle link 57 by means of stud 64 the end of which protrudes through web portion 57a. A coil spring 66 under compression has one end positioned around the protruding end of stud 64 and presses at that end against web portion 57a and at the other end against oversize washer 68 which in turn rests on shoulders formed on the adjacent end of vertically extending member 51a of switch lever 51.

In the manner characteristic of such switches, the movement of toggle link 57 to a position slightly past its midposition results in a snap action of switch lever 51 to open the contacts at one of its ends and close those at its opposite end substantially simultaneously. Spring 66 provides, in either position, sufficient tension to hold the contacting members securely together.

Details of cam C are shown in Figure 4 wherein two cam members 70, one each of which is secured, as by welding, to a bracket 71 which bracket in turn is secured by means of a bolt 72 to crosshead 24, engage opposite sides of roller 62 and are so configurated as to impart sidewise motion to roller 62 and in turn toggle link 57, as the crosshead moves either up or down.

Figure 5 illustrates diagrammatically a position indicator circuit arrangement using toggle switches TS1 to TS4 of Figure 1. Alternating power from any suitable source (not shown) is supplied over lines W12 and W13 to position indicator lamps or bulbs PI-1 to PI-5, the number suffix of each lamp corresponding to the floor landing for which that lamp is provided. These lamps or bulbs PI-1 to 5 may be of the incandescent type and may be mounted for example on a panel located in the lobby of the building, along with similar lamps for other cars in the group or may be mounted in a panel located within the car for which they are provided.

Supply line W12 is electrically connected through manual switch contacts MS1 to movable contacts 54 and 55 of toggle switch TS4. Manual switch MS is utilized to remove the position indicator circuit from operation. Stationary contact 43 of toggle switch TS4 is connected to one side of position indicator lamp PI-5, the other stationary contact 44 being connected to movable contacts 54 and 55 of toggle switch TS3. The stationary contacts 43 and 44 of toggle switch TS3 are similarly connected to lamp PI-4 and movable contacts 54, 55 of toggle switch TS2, respectively, while the stationary contacts 43 and 44 of toggle switch TS2 are in turn similarly connected to lamp PI-3 and movable contacts 54, 55 of toggle switch TS1, respectively. Stationary contacts 43 and 44 of toggle switch TS1, which switch is mounted on a floor bar 26 corresponding to the second floor landing (see Figure 1), are connected to lamp PI-2 provided for the second floor landing and to lamp PI-1 provided for the first floor landing, respectively. The other side of each lamp PI-1 to 5 is connected to supply line W13. The cam C is shown for the position of the car at the first floor landing in which position lamp PI-1 is illuminated, the circuit extending from supply line W12 through contacts MS1, contacts 55 and 44 of switches TS4 to TS1, lamp PI-1 to supply line W13.

The operation of the arrangement can be visualized with reference to Figures 1 and 5. As the elevator car travels upward from the first floor landing, steel tape 15 rotates driving wheel 16 which, through the intermediary of shaft 21, bevel gears 23 and vertical screw 22, drives crosshead 24 in its vertical path. As crosshead 24 moves

upward, cam C, mounted thereon, actuates toggle switch TS1 at a point corresponding to a position substantially midway between the first and second floor landings. This switch "snaps" to its other position separating its contacts 44 and 55 to extinguish position indicating lamp PI-1 and immediately engaging its contacts 54 and 43 to light lamp PI-2, indicating the position of the car at the second floor landing.

As the car continues upward, toggle switches TS2 to TS4 are similarly actuated in sequence by cam C to indicate the position of the car at the third, fourth and fifth floor landings by lighting lamps PI-3 to 5 successively. As has been previously stated, the persistence of human vision, coupled with the fast acting nature of switches TS1 to 5 is effective to indicate continuously the position of each car in its hoistway. The use of incandescent lamps, as in the preferred embodiment, results in an even greater of continuity of indication, since the cooling rate of such lamps tends to maintain a previously energized lamp illuminated, when it is deenergized, until the next successively energized lamp becomes illuminated.

As the car moves downward, cam C actuates switch TS4 at a point corresponding to the position of the car substantially midway between the fifth and fourth floor landings. This switch "snaps" to its other position separating its contacts 54 and 43 to extinguish lamp PI-5 and immediately engaging its contacts 55 and 44 to light lamp PI-4, the latter circuit extending through W12, MS1, contacts 55 and 44 of switch TS4, contacts 54 and 43 of switch TS3, PI-4 and W13. As the car proceeds downward, switches TS1 to 3 are actuated in reverse sequence, lighting lamps PI-3 to PI-1 successively to indicate continuously the position of the car.

This continuous indication of the position of each car in a group of cars serving a common main lobby enables intending passengers at that main lobby and the starter to ascertain readily the relative position of the cars so that they may anticipate which car will be the next to arrive at that lobby, thereby minimizing the passenger loading time at the lobby. In the case of a car stranded between floor landings, the subject position indicator allows maintenance personnel to determine quickly its location in the hoistway. Also, passengers within a car equipped with the subject invention may readily determine the position of that car at any given instant and since the transfer of the indication of the position of the car occurs substantially midway between floor landings, such passengers are advised that the car is arriving at their destination before it actually arrives there, tending to prepare them for exiting, thereby decreasing the passenger discharge time at a floor landing.

Although in this described embodiment of the invention the toggle switches have been shown and described as being mounted on floor bars of a selector, they may, without departing from the scope of the invention, be mounted in the hoistway and be actuated by a cam carried by the car. Also, in elevator installations in which one or more cars serve only the upper floor landings of a building and operate "express" past the lower floor landings, one of the toggle switches TS1 to 5 and one of the position indicator lamps PI-1 to 5, such as switch TS1 and lamp PI-2 may be so positioned and designated as to indicate, when they are operated, that a car is traveling in the express portion of its hoistway.

As changes can be made in the above described construction and many apparently different embodiments of this invention can be made without departing from the scope thereof, it is intended that all matter contained in the above description or shown on the accompanying drawing be interpreted as illustrative only and not in a limiting sense.

What is claimed is:

1. In an elevator installation in which an elevator car travels in a hoistway, car position indicating mechanism for continuously indicating the position of said car in said hoistway, said car position indicating mecha-

nism comprising, a plurality of light sources, one each of which corresponds to one of several predetermined positions of said car in said hoistway, a source of energy for energizing said light sources, switching means including a plurality of mechanically actuatable electric switches for selectively connecting said energy source to said light sources, said plurality of switches being one less than said predetermined positions, and camming means operable in accordance with movement of said car in said hoistway for selectively actuating said switches for causing said energy source to energize a first one of said light sources corresponding to a first one of said predetermined positions of said car in said hoistway and for removing said energy source from said first one of said light sources and at the same time substantially instantaneously causing said energy source to energize a second one of said light sources corresponding to a second one of said predetermined positions of said car in said hoistway as said car travels in said hoistway from said first predetermined position to said second predetermined position, thereby continuously indicating the position of said car in said hoistway.

2. In an elevator installation in which an elevator car traveling in a hoistway serves a plurality of floor landings of a building, car position indicating mechanism comprising, a plurality of light sources, one each of which is provided for each floor landing served by said car, an energy source for energizing said light sources, a plurality of mechanically actuatable electric switches adapted for selectively connecting said energy source to said light sources, said plurality of switches being one less than said served landings, and control means operatively responsive to the position and movement of said car in said hoistway for selectively actuating said switches for applying said energy source to the one of said light sources corresponding to the present position of said car and for deenergizing said light source and instantaneously energizing a second one of said light sources corresponding to the next position of said car in accordance with the direction of travel of said car as said car travels to said next position, thereby continuously indicating the position of said car in said hoistway.

3. Car position indicating mechanism as claimed in claim 2 wherein said means for selectively applying said energy source to one of said light sources comprises a selector mechanism having a plurality of horizontally disposed floor bars mounted in vertical spaced relationship to each other at predetermined points corresponding to said floor landings served by said car, each of said floor bars except the floor bar corresponding to the lowermost floor landing served by said car having mounted thereon a snap action toggle switch of the single pole double throw latching type, said toggle switches being mounted in vertical alignment with each other, and said selector also having a crosshead actuatable along a vertical path adjacent to said toggle switches in accordance with movement of said car, said crosshead having mounted thereon a cam in position to engage and actuate said toggle switches in sequence as said crosshead is actuated along said vertical path, said toggle switches being adapted when so actuated, for electrically disconnecting said power source from the light source provided for the floor landing corresponding to the last previous position of the car and instantaneously connecting said power source to the light source provided for the floor landing adjacent to that floor landing in the direction of travel of said car as said car arrives substantially midway between said adjacent floor landings.

4. In an elevator installation in which an elevator car traveling in a hoistway serves a plurality of floor landings, car position indicating mechanism for continuously indicating the position of said car in said hoistway, said position indicating mechanism comprising, means including a member which is actuatable along a predetermined path in accordance with movement of said car but at a speed proportional to the speed of said car, a plurality of

electric light bulbs, one each of which is provided for each of said floor landings, a source of electrical energy for energizing said light bulbs, and a plurality of mechanically actuated snap action toggle switches, said plurality being one less than the number of said floor landings served, said switches being positioned along said predetermined path in spaced relation to each other and in position to be sequentially actuated by said member and being adapted to interconnect selectively said energy source to the light source corresponding to the position of the car for continuously indicating that position.

5. In an elevator installation in which an elevator car traveling in a hoistway serves a plurality of floor landings, car position indicating mechanism for continuously indicating the position of said car in said hoistway, said position indicating mechanism comprising, means including a member which is actuatable along a predetermined path in accordance with movement of said car but at a speed proportional to the speed of said car, a plurality of electric light bulbs, one each of which is provided for each of said floor landings, a source of electrical energy for energizing said light bulbs and instantaneous switching means adapted for instantaneously transferring the electrical connection of said energy source from one light source to another in accordance with movement of said member to energize said light sources in accordance with car movement for continuously indicating the position of said car.

30 6. Car position indicating mechanism as claimed in claim 5 wherein said instantaneous switching means comprises a plurality of snap action toggle switches positioned at predetermined points along said predetermined path in position to be actuated by said member for electrically connecting said energy source to said light source corresponding to the next position of said car while at the same time disconnecting said energy source from a previously energized light source corresponding to the last previous position of said car.

40 7. In an elevator installation in which an elevator car traveling in a hoistway of a building serves a first floor landing and also a plurality of floor landings located above said first floor landing, and in which selector mechanism is provided, said selector mechanism including a crosshead which is actuatable along a fixed vertical linear path in accordance with movement of said car but at a speed proportional to the speed of the said car, and a plurality of horizontally disposed floor bars mounted in vertically spaced relationship to each other along said path at predetermined points corresponding to the positions of said floor landings in said building; a car position indicator being characterized in that there are provided a plurality of incandescent light bulbs, one each of which corresponds to one of said floor landings served by said car, an electric power source for energizing said light bulbs, said power source having two output terminals, said light bulbs having one side electrically connected in parallel to one of said output terminals, a plurality of snap action toggle switches of the single pole double throw latching type, one each of which is mounted in vertical alignment with each other on said floor bars corresponding to said floor landings located above said first floor landing, said toggle switches each having two relatively stationary contacts and a switch lever with two relatively movable contacts in position to engage said stationary contacts, the other output terminal of said power source being electrically connected to said switch lever and in turn the movable contacts of the uppermost toggle switch, one stationary contact of that toggle switch being electrically connected to the other side of the light bulb corresponding to the uppermost floor landing and the other stationary contact being electrically connected to the switch lever of the toggle switch located directly below said uppermost toggle switch, all other of said toggle switches except the lowermost toggle switch having one stationary contact connected to its correspond-

ing light bulb and the other connected to the switch lever of the toggle switch located directly below it, the lower-most toggle switch having one stationary contact connected to its corresponding light bulb and the other stationary contact connected to the light bulb corresponding to said first floor landing, and a cam mounted on said crosshead in position to engage and actuate said toggle switches in sequence as said crosshead is actuated along said path in accordance with the movement of said car in said hoistway for sequentially connecting said light bulbs across said power source in accordance with car

movement to indicate continuously the position of the car.
